UNITED STATES PATENT OFFICE.

LARS W. BODINSON, OF AURORA, ILLINOIS, ASSIGNOR TO THE AMERICAN WELL WORKS,
OF AURORA, ILLINOIS, A CORPORATION OF ILLINOIS.

DEEP-WELL PUMP.

1,289,624.

Specification of Letters Patent. Patented Dec. 31, 1918.

Application filed March 12, 1915. Serial No. 13,868.

To all whom it may concern:

Be it known that I, LARS W. BODINSON, a citizen of the United States, residing at Aurora, in the county of Kane, State of Illinois, have invented certain new and useful Improvements in Deep-Well Pumps, of which the following is a specification, reference being had to the accompanying drawings.

10 This invention relates to deep well pumps of the plunger type, and it has for its principal object the provision of a new and improved form and arrangement of parts in a single-acting pump of this type whereby 15 an increased amount of water can be pumped. As will be readily appreciated, in the use of a double-acting plunger pump, in the application of power to the pump rod for the down stroke of the plunger the rod 20 has a tendency to buckle so as to be brought into contact with adjacent parts between its bearings, causing abnormal wearing of the parts. In wells in some formations through 25 which it has been found impossible to drill perfectly straight, the wear caused by the buckling of the pump rods is so great as to make the use of double-acting pumps undesirable.

It is another object of my invention to 30 provide a construction in an improved pump of the type described by reason of which the pump rods and the plungers operated thereby may be drawn upward out of operative position whenever desired for replacing or 35 repairing the plungers. It is another object of my invention to provide such a construction in which one or more of the cylinders in which the plungers operate may be raised to the surface with the plungers by means of 40 the pump rods without the removal of the pump casings. It is another object of my invention to provide improvements in the system of pump rods used for operating the plungers, involving improved bearing means 45 and suitable means for lubricating such bearings. It is another object of my invention to improve devices of this type in sundry details hereinafter pointed out.

The preferred means by which I have 50 accomplished my objects are illustrated in the accompanying drawings and are hereinafter specifically described. That which I believe to be new and desire to claim by this application is set forth in the claims.

55 In the drawings, the figures are sectional

views, being broken away at many points for varying distances in order to illustrate the construction fully without unduly extending the views.

Figure 1 is a view showing the upper 60 part of the pump and the means for connecting the pump rods to the actuating mechanism;

Fig. 2 is a view of the upper part of the pumping mechanism located at the bottom 65 of the well;

Fig. 3 is a continuation downward from the part shown in Fig. 2, and Fig. 4 is a continuation downward from the parts shown in 70 Fig. 3;

Figs. 5 to 12, inclusive, are horizontal cross-sections taken upon the correspondingly-numbered section lines of Figs. 2, 3 and 4;

Fig. 13 is a view showing one form of the 75 devices by which the pump rods are connected together, and are spaced relative to each other;

Fig. 14 is a cross-section taken on line 14—14 of Fig. 15, Fig. 15 being a central 80 vertical section showing a modified form of connections for the sections of pump rod;

Fig. 16 is a view showing still another 85 form of coupling devices for connecting the different sections of pump rod;

Fig. 17 is a view of the upper portion of a modified form of pumping apparatus located in the bottom of a well, and Figs. 18, 19 and 20 show successively lower portions 90 of such pumping apparatus;

Fig. 21 shows another modified form of the upper portion of the pumping apparatus located at the bottom of the well, and Figs. 22 and 23 show successively lower portions 95 of such pumping apparatus;

Fig. 24 shows still another modified form of the upper portion of the pumping apparatus located at the bottom of the well, and Figs. 25 and 26 show successively lower portions 100 of such pumping apparatus.

Referring to Figs. 1 to 13, inclusive, in which corresponding parts are indicated by the same reference characters, 30 indicates a T-connection mounted by means of screw-threads upon the upper end of a well-pipe 105 31 extending downward into the well 32. Connected by means of screw-threads to the T-connection 30 is a water-delivery pipe 33 by which the water is adapted to be led to any suitable point. As is clearly shown in 110

Fig. 1, the upper end of the connection 30 is closed by a plate 34 through which a tubular pump rod 35 extends, a stuffing-box 36 of any suitable type being interposed between the pump rod 35 and the plate 34. A cross-head 37 is mounted by means of screw-threads upon the upper end of the pump rod 35, being locked in position thereon by means of a jam-nut 38. A cap 39 closes the upper end of the pump rod 35 about a second pump rod 40 extending downward into the tubular pump rod 35, suitable packing 41 being held about the pump rod 40 in a suitable recess in the cap 39 adjustably closed at its upper end by a suitable gland 42. The upper end of the pump rod 40 has a cross-head 43 connected to it by means of screw-threads, the cross-head being locked in position by means of jam-nuts 44. Communicating with the interior of the pump rod 35 near its upper end is a pipe or tube 45, in the construction shown a valve 46 of any suitable type being interposed for controlling the flow from the pipe 45 to the tubular pump rod 35. The cross-heads 37 and 43 are designed to be reciprocated vertically by any suitable mechanism, not shown. It will be understood that these cross-heads may be reciprocated always in opposite directions whereby one of the pump rods reaches its highest point when the other pump rod reaches its lowermost position, the pump rods being adapted to travel always in opposite directions. I prefer, however, to have the cross-heads reciprocated vertically by a driving means such as that shown and claimed by Letters Patent of the United States, No. 1,124,295, issued on January 12, 1915, to The American Well Works as the assignee of Matthew T. Chapman, by the use of which construction the upward stroke of each pump rod is caused to begin before the other pump rod reaches its uppermost position.

Referring particularly to Fig. 13, which shows one form of pump rods designed to be used, it will be seen that the pump rod 40 is composed of sections joined together by means of screw-threaded couplings 47 and that the pump rod 35 is likewise formed of sections joined together by screw-threaded couplings 48. At the lower end of each section of the pump rod 35 a block 49 of wood, or of any other suitable material, is secured in any suitable manner, said block preferably having a close fit in the section 35, but having a suitable working fit about the pipe 40. By the use of a plurality of such blocks 49 throughout the line of pump rod sections 35—40, the inner pump rod is spaced away from the tubular pump rod so as to avoid undue wear between said rods. The pipe 45 is adapted to be connected at its outer end with any suitable source of lubricant, water, oil, grease or any other suitable

lubricant being adapted to be used for this purpose. It will be understood that in cases where the pump is being used for raising water for domestic purposes, it is preferred that pure filtered water be used for lubricating purposes in order not to impair the potability of the water.

Referring now to Figs. 2, 3 and 4, it will be seen that the pumping apparatus at the bottom of the well comprises a cylinder 50 secured by means of a coupling 51 to the lower end of the well pipe 31, a cylinder 52 of smaller diameter than the cylinder 50 secured to the lower end of said cylinder 50 by means of a coupling 53, pistons or plungers 54 and 55 adapted to be reciprocated in the cylinder 50, and pistons or plungers 56 and 57 adapted to be reciprocated in the cylinder 52. As will be seen by the detailed description hereinafter, the piston 54 and the piston 57 are adapted to be reciprocated in unison by the pump rod 40, while the two intermediate pistons 55 and 56 are adapted to be reciprocated in unison by the pump rod 35.

Coming now to a more detailed description of the pumping apparatus at the bottom of the well, 58 indicates a sleeve (see Figs. 2 and 5) secured by means of screw-threads to the lower end of the pump rod 35. The sleeve 58 is connected by means of webs 59 with a sleeve 60 having a sliding fit in the well pipe 31, serving thus to hold the pump rods centered relative to the well pipe. Formed integrally with the sleeve 58 in the construction shown is a head 61 which has a working fit upon the pump rod 40. Secured by means of screw-threads upon the lower end of the pump rod 40 below the head 61 is a thimble 62, in the lower end of which is secured by means of screw-threads a spider 63 (see Fig. 6) comprising a plurality of arms 64, a sleeve 65, and radially-extending webs 66 engaging at their outer ends the inner surface of the well pipe 31. Secured to the sleeve 65 by means of screw-threads and extending downwardly therefrom, is a cylindrical pump rod section 67. Secured by means of screw-threads to the spider 63 at its central point is another pump rod section 68, both of such sections 67 and 68 being adapted to be reciprocated in unison by the pump rod 40, as will be readily understood. A jam-nut 69 is mounted on the upper end of the pump rod section 68 for further securing such section in position. Slidably mounted upon the pump rod section 68 within the cylindrical pump rod section 67 is a head 70 (see Fig. 7). The head has connected to it by means of webs 71 a coupling 72, to the lower end of which there is connected by means of screw-threads a tubular pump rod section 73, water being adapted to pass through the coupling 72 about the pump rod section 68 between the

webs 71. The heads 61 and 70 are rigidly connected to each other by a plurality of links 74 which pass through suitable vertically-extending openings through the said heads, nuts 75 being provided on the ends of said links for holding the heads firmly in contact with suitable shoulders on the links. As will be seen from the above description, the pump rod section 73 is virtually an extension of the pump rod 35, being adapted to be actuated in unison therewith, the break in the tubular pump rod between the heads 61 and 70 being necessary in order to permit the connection of the pump rod 40 with the pump rod section 67 surrounding the pump rod section 73.

The plunger 54 comprises an annular outer portion 76 joined by radially-extending webs 77 to an inner sleeve portion 78 which is joined at its upper end by means of a coupling 79 to the lower end of the cylindrical pump rod 67. Extending upward about the tubular pump rod section 73 inside of the cylindrical pump rod section 67 is an annular flange 80, which, in the construction shown, is formed integrally with the coupling member 79, such flange being provided for the reception of packing 81 of any suitable type held adjustably in position 30 therein by means of a gland 82 secured by means of screw-threads upon the upper end of the flange 80. Suitable packing rings 83 are mounted upon the outer face of the annular outer portion 76 of the plunger 54, being held adjustably in position thereon by suitable nuts 84. The upper end of the annular passage through the plunger 54 between the webs 77 is adapted to be closed by a valve 85 which is slidably mounted upon the sleeve portion 78 of the plunger so as to be adapted to rise freely thereon, being limited in its upward movement by contact with the coupling member 79.

The plunger 55 comprises a sleeve 86 by 45 which the lower end of the tubular pump rod section 73 is joined to the upper end of a tubular pump rod section 87, said sleeve portion 86 being joined by means of webs 88 with an annular outer portion 89 having a working fit in the cylinder 50, suitable packing 90 being interposed between said two parts. A valve 91 is slidably mounted upon the sleeve-portion 86 adapted to close the annular passage between the webs 88, the valve 91 being limited in its upward movement by a cap 92 mounted by means of screw-threads on the upper end of the sleeve 86.

The coupling member 53 comprises two tapering sleeves 93 and 94 joined by webs 95, in the construction shown the said parts being formed integrally with each other. As is shown in Fig. 3, the cylinder 52 is made of slightly smaller diameter than the cylinder 50 in order to accommodate the 60 taper of the sleeves 93—94 to provide a

tapering seat for the valve-cage 96 (see Figs. 3 and 9). This valve-cage 96 comprises a bell-shaped sleeve portion 97 slidably mounted upon the pump rod section 87 and having suitable packing 98 interposed between its inner face and the pump rod section 87, such packing being held adjustably in position by a cap sleeve 99. An annular outer portion 100 is secured to the bell-like portion 97 by means of webs 101, in the construction shown said three portions being formed integrally with each other. The outer face of the annular portion 100 and the outer face of the lower portion of the bell-like sleeve 97 are shaped to conform to the tapering portions 93 and 94 of the coupling 53, respectively, suitable packings 102—103, respectively, being provided. A valve 104 is slidably mounted upon the upper end of the sleeve 97, being limited in its upward movement thereon by a sleeve 105 secured by means of screw-threads on the upper end of said sleeve, the valve 104 being adapted to close the annular passage-way between the webs 101. As will be appreciated from an inspection of Fig. 3, the cage 96 and the coupling 53 provide a free passage-way between the interior of the cylinder 50 and the exterior thereof, except as such passage-way is closed by the valve 104; the cylinders 50 and 52 are properly secured together; and the cage 96 carrying with it the valve 104 is adapted to be lifted readily out of position in the coupling member 53. By reason of the taper of the parts the cage 96 is adapted 100 to assume proper position relative to the coupling 53 upon the cage 96 being let down therein.

As is best shown in Figs. 4 and 10, 106 indicates a coupling comprising a sleeve 107 connected by means of screw-threads to the lower end of the tubular pump rod section 87 and a sleeve 108 connected as hereinafter described to the plunger 56. The sleeves 107 and 108 are connected together by means of webs 109 whereby the lower end of the tubular pump rod 87 opens into the cylinder 52. The piston or plunger 56 comprises a sleeve 110 joined by webs 111 to an annular outer portion 112. The upper end of the sleeve 110 is joined by means of screw-threads to the sleeve 108, suitable packing 113 being provided between the sleeve 110 and the pump rod section 68, such packing being adjustably held in position by means of a sleeve 114 secured by means of screw-threads in the upper ends of the sleeves 108 and 110. A valve 115 is slidably mounted upon the sleeve 110 being limited in its upward movement thereon by the sleeve 108, said valve being adapted to close the annular passage-way between the webs 111. Suitable packing 116 is provided between the outer face of the annular portion 112 and the inner face of the cylinder 52.

The plunger 57 comprises a sleeve 117 mounted by means of screw-threads upon the lower end of the pump rod section 68, as shown in Fig. 4 a jam-nut 118 being employed for locking the said sleeve in position thereon. The sleeve 117 is connected by means of radially-extending webs 118 with an annular outer portion 119, the sleeve 117, the webs 118 and the annular portion 119 of the plunger being preferably formed integrally with each other. The plunger 119 is provided with suitable packing 120 on its outer face engaging the inner face of the cylinder 52. A valve 121 is slidably mounted upon the upper end of the sleeve 117, being limited in its upward movement thereon by a nut 122 secured by means of screw-threads upon the upper end of said sleeve. The valve 121 is adapted to close the annular passage-way between the sleeve 117 and the annular portion 119 of the piston or plunger 57, as will be readily understood.

A sleeve 123 is mounted by means of screw-threads upon the lower end of the cylinder 52, providing a tapering seat for the annular outer portion 124 of a valve-cage, such annular portion 124 being adapted to fit closely against its seat. Webs 125 serve to connect the annular portion 124 of the valve-cage with a sleeve portion 126, the sleeve 126, webs 125 and annular portion 124 being preferably formed integrally with each other. A valve 127 is slidably mounted upon the sleeve 126, being limited in its upward movement thereon by a sleeve 128 mounted by means of screw-threads upon the upper end of said sleeve. The valve 127 is adapted to close the passage-way between the webs 125 of the valve-cage, serving thus to close the lower end of the cylinder 52. Radially-extending flanges 129 are formed with the sleeve 123 serving to center said sleeve in the well 32. As will be readily understood, the said valve-cage is adapted to be lifted out of engagement with the sleeve 123, and is adapted to resume tight gripping engagement with said sleeve upon being again lowered through the cylinder 52.

With the cross-heads 43 and 37 being reciprocated by any suitable means,—for example, by a device of the type shown in Patent No. 1,124,295, above referred to,—the pistons or plungers 54 and 55 will be reciprocated in opposite directions in the cylinder 50, and the pistons or plungers 56 and 57 will be reciprocated in opposite directions in the cylinder 52. As before explained, in such operation the upward stroke of either piston in either one of the cylinders begins before the end of the upward stroke of the other piston in the same cylinder, but generally speaking the plungers may be said to be operated in opposite directions.

With the pistons 56 and 57 being oper-

ated in opposite directions in the cylinder 52 as just described, when the piston 56 is moved upward in the said cylinder the valve 115 serves to close the upper end of the said piston causing the water to rise 70 past the valves 121 and 127 which are located in the said cylinder below the piston 56. In this upward movement of the piston 56 the water in the upper end of the cylinder 52 is forced upward through the pump 75 rod section 87, through the pump rod section 73, into the cylindrical pump rod section 67 and thence upward through the well pipe 31 to the surface. Just before the plunger 56 reaches its uppermost position, 80 the plunger 57 will have started upward, drawing water past the valve 127 to fill the lower end of the cylinder 52. Upon the continued upward movement of the plunger 57 with the plunger 56 at the same time 85 moving downward, the water in the cylinder 52 between the plungers 56 and 57 will be forced upward past the valve 115, a portion of such water serving to fill the upper end of the cylinder 52 above the descending piston 56 and the remainder of the water being forced upward through the tubular pump section 87 as just above described.

While the piston 56 is being forced upward in the cylinder 52 the piston 55 is also 95 being forced upward in the cylinder 50, filling the lower end of the cylinder 50 with water rising past the valve 104. Shortly after the start of the upward stroke of the piston or plunger 55, the piston 54 is started 100 on its downward stroke, and the water in the cylinder 50 between the plungers 54 and 55 is consequently forced upward past the valve 85 in the plunger 54, a portion of such water serving to fill the upper end of 105 the cylinder 50 above the descending piston 54 and the remainder thereof being caused to rise through the well pipe 31. Upon the reversal of direction of movement of the piston 54 the water in the cylinder 50 above 110 the piston 54 is forced upward through the well pipe 31, water being forced upward past the valves 104 and 91 for filling the cylinder 50 between the plungers 54 and 55.

With the pump rods 40 and 35 being reciprocated by such a device as that shown in the Chapman Patent, 1,124,295, above referred to, the column of water rising through the well pipe 31 will be kept in continuous upward movement, thus avoiding 115 the necessity for overcoming the inertia of the water where it is permitted to stop between successive strokes of the various plungers. All of the operation of raising the water is effected by the upward movement 120 of the pump rod parts, in which upward movement of the pump rods the tendency is to cause the pump rods to straighten their alignment relative to each other and relative to the well pipe rather than to 125 130

buckle as is the case in a double-acting pump. By reason of the construction of the parts, the pump rods are free to be withdrawn readily carrying upward with them 5 the entire system of valves and plungers with the exception of the valve 127, the cage 96 with its valve 104 being adapted to be raised with the pump rod by reason of the coupling 106 being brought into contact 10 with the cap or gland 99, serving to lift the cage as a whole from its seat. The valve 127 is adapted to be withdrawn if desired by the use of any suitable mechanism, such valve being adapted to be lifted freely from 15 its seat in the sleeve 123. By the use of the bearing-blocks 49 in the tubular pump rod sections 35, the pump rods are held in proper alignment relative to each other so as to avoid any undue friction or wear upon 20 such parts. By the expedient of forcing pure water or other suitable lubricant down the tubular pump rod 35 the bearings between the pump rod 40 and the blocks 49 are kept in good working condition. If de- 25 sired the water for lubricating purposes can be forced downward through the tubular pump rod 35 so as to wash out from the bearings any grit or sand which might be lodged therein, such supply of water under 30 pressure serving also to wash out any grit or sand which might work its way between the head 61 and the lower end of the pump rod 40. Indeed this result would be accomplished under normal conditions whether 35 or not the water were supplied to the tubular pump rod 35 under pressure, the head of the water in such pump rod above the part 61 being sufficient for maintaining the bearing of the part 61 upon the pump rod 40 in proper condition. While I have 40 shown no means of communication between the interior of the tubular pump rod 35 at its lower end and the well pipe 31 about the pump rod 35 except through the working bearing of the head 61 upon the pump rod 40, it will be understood that I do not wish to restrict myself to this particular construction except as hereinafter specifically 45 claimed, inasmuch as any suitable expedient may be adopted for making such communication more ample if the communication through the bearing of the head 61 is found to be insufficient.

In Figs. 14 and 15 in which a slightly modified form of coupling devices is shown, I have indicated corresponding parts by the same reference characters as in Figs. 1 to 13, but with the addition of the exponent "a". In the construction there shown a coupling 50 sleeve 130 is used in lieu of the sleeve 48 shown in Fig. 13, such sleeve 130 being joined by means of webs 131 to an outer sleeve member 132 adapted to have a sliding fit in the well pipe 31^a. A block 133 of 55 wood or other suitable material is mounted

in the sleeve 130 between the sections of the tubular pump rod 35^a, such block 133 having a working fit upon the pump rod 40^a, serving as a bearing therefor.

In Fig. 16, which shows still another form 70 of coupling device, I have indicated corresponding parts by the same reference characters, but with the addition of an exponent "b." In this construction a sleeve 134, having fixed therein a block of wood or other 75 suitable material 135, is used for connecting the sections of the pump rod 35^b. A coupling 136 having a tapering threaded opening for the reception of the ends of the sections of the pump rod 40^b is used for connecting said sections in lieu of the coupling sleeve 47 shown in Fig. 13.

In Figs. 17, 18, 19 and 20, which show a modified form of pumping apparatus at the bottom of the well, I have indicated corresponding parts by the same reference numerals as are used in Figs. 1 to 13, but with the addition of an exponent "c." In the construction shown in said figures, the lower end of the cylinder 50^c and the upper end of the 85 cylinder 52^c are joined together by a modified form of coupling device by which a valve at this point is dispensed with. In this construction, 137 indicates a sleeve secured by means of screw-threads upon the lower 90 end of the cylinder 50^c, and 138 indicates a second sleeve formed integrally with the sleeve 137, joined by means of webs 139 to a third sleeve 140 which is connected by means of screw-threads to the upper end of the 100 cylinder 52^c. The upper portion of the sleeve 140 and the inner face of the sleeve 138 provide tapering seats in alignment with each other for a member 141 serving to close the upper end of the cylinder 52^c and to afford a suitable outlet from the lower end of the cylinder 50^c. The member 141 is provided with suitable packing 142 at its lower 105 end in engagement with the inner face of the tapering sleeve 140 and is provided with 110 suitable packing 142 between its lower end and the tubular pump rod section 87^c. The said closure member 141 comprises also radially-extending webs 144 connected at their outer edges to a sleeve 145 having suitable 115 packing 146 in engagement with the tapering seat provided by the sleeve 138. The construction is such that the member 141 and the parts connected therewith serve to close tightly the upper end of the cylinder 52^c and 120 provide an annular passage co-operating with the annular passage between the sleeves 138 and 140 for providing a suitable port from the lower end of the cylinder 50^c. The said closure member 141 is adapted to be lifted 125 readily out of position by means of the coupling 106^c upon the withdrawal of the pump rods.

147 indicates a well tube section secured by means of screw-threads upon the sleeve 138 130

and extending downward therefrom about the cylinder 52^c. At its lower end the well tube section 147 has secured to it by means of screw-threads a sleeve 148 corresponding 5 to the sleeve 123 secured to the lower end of the cylinder 52, as shown in Fig. 4, the sleeve 148 providing a tapering seat for the annular outer member 124^c which supports the valve 127^c. The sleeve 148 is provided with 10 radially-extending flanges or ribs 149 and has secured to its lower end by means of screw-threads the upper end of a downwardly-extending pipe 150.

By the provision of the pipe or tube 147 15 about the cylinder 52^c leading downward from the cylinder 50^c the necessity for placing the lower end of the cylinder 50^c below the level at which the water is adapted to stand in the well is avoided. The valve 127^c 20 is also adapted to perform the function of the two valves 127 and 104 of the construction first described.

In Figs. 21, 22, and 23, which show a modified form of structure, the parts corresponding 25 to the parts shown in Figs. 1 to 13 are indicated by the same reference characters, but with the addition of an exponent "d." In this construction a cylinder 151 of the same size as the cylinder 50 is provided in 30 lieu of the cylinder 52 of Figs. 1 to 13, the cylinder 151 being joined at its upper end to the cylinder 50 by a coupling comprising a bell-shaped sleeve 152 and a sleeve 153 joined to the sleeve 152 by means of webs 35 154. The valve 104^d is slidably mounted upon the upper end of the sleeve 152 so as to be adapted to close the annular opening between the sleeves 152 and 153, being limited in its upward movement thereon by a 40 collar 155 secured by means of screw-threads above the valve 104^d. Suitable packing 156 is held in position between the sleeve 152 and the tubular pump rod section 87^d by means of an adjustable gland 157. In the construction 45 shown in said Figs. 21, 22 and 23, the pump rods together with the pistons and valves are incapable of being removed except upon the removal of the well pipe 31^d and the cylinders 50^d and 151.

50 In Figs. 24, 25 and 26, the parts which correspond to the structure shown in Figs. 1 to 13 are indicated by the same reference characters, but with the addition of an exponent "e." In this construction, the well pipe is 55 indicated by the numeral 158 and is continued downward past the upper end of the upper cylinder which is indicated by the numeral 159. A sleeve 160 is mounted by means of screw-threads upon the upper end 60 of the cylinder 159 serving to hold the cylinder centered relative to the well pipe 158. The lower end of the well pipe 158 is joined to the upper end of the lower cylinder 52^e by means of a coupling comprising two sleeves 65 161 and 162 joined by webs 163. In this con-

struction the lower end of the upper cylinder 159 is adapted to be closed by a valve 164 slidingly mounted upon the upper end of a sleeve 165 which is joined by means of webs 166 to an outer sleeve member 167, the said valve 164 being limited in its upward opening movement by a sleeve 168 mounted by means of screw-threads upon the upper end of the sleeve 165. Suitable packing 169 is interposed between the sleeve 165 and the tubular pump rod section 87^e, said packing being held in position by an adjustable gland 170. By this construction the upper cylinder 159 is adapted to be withdrawn from the well together with the pump rods, pistons and valves, being free to be lifted out of the tapering seat provided by the sleeves 161 and 162, the valve-cage at the bottom of the cylinder being adapted to seat itself, upon the re-insertion of the mechanism in the well tube, in proper position relative to the annular passage between the sleeves 161 and 162.

While I have shown valve mechanism in connection with each form of structure illustrated adapted to act independently of the valves in the plungers for preventing the downward movement of the water, it will be understood from a study of the operation of the device that such stationary valve mechanism is not essential to the operation of the pump, and I do not wish to restrict myself to the use of such stationary valve mechanism except as hereinafter specifically claimed. Indeed, it is probable that, during the normal operation of the pump, when driven by such a device as that shown by the Chapman Patent, 1,124,295, above referred to, the valves 104 and 127 of the construction of Figs. 1 to 13 and the corresponding valves of the other constructions would not close at all inasmuch as there is a continuous upward flow of water through each of the cylinders. These valves serve, however, to relieve the strain upon the piston valves when the pump is not in operation and the employment of such valves is therefore to be desired.

While I have described the parts 50 and 52 of Figs. 1 to 13 and the corresponding parts of the other figures as cylinders, it will be understood that such parts might equally well be termed well pipe sections or well tube sections serving as cylinders, with the possible exception of the cylinder 159 which is removable relative to the well pipe. It will be understood that I do not wish to be restricted to the use of separate cylinders in lieu of extensions of the well pipe of proper size and description except as the claims may specifically designate the cylinders as being formed separately or as being removable from the well pipe, the word cylinder being used broadly in the specification and claims to indicate the tube or portion of a tube or other receptacle within which the plungers are operated for raising the water.

What I claim as my invention and desire to secure by Letters Patent, is—

1. The combination of a well-pipe, single-acting pumping means comprising two plungers adapted to be reciprocated in opposite directions in alinement with said well-pipe adapted to coöperate for forcing a supply of water into the well-pipe, and other single-acting pumping means comprising two other plungers adapted to be reciprocated in opposite directions in alinement with said well-pipe below said first-named plungers adapted to coöperate for forcing a separate supply of water into said well-pipe.

15 2. The combination of a well-pipe, single-acting pumping means comprising two plungers adapted to be reciprocated in alinement with said well-pipe and adapted by coöperation to force a supply of water into the well-20 pipe, two plunger rods connected with said plungers respectively for reciprocating them in opposite directions, and other single-acting pumping means comprising two other plungers adapted to be reciprocated in alinement with said well-pipe below said first-named plungers and adapted by coöperation to force a separate supply of water into said well-pipe independently of said first-named plunger, said last-named plungers being connected with said plunger-rods respectively.

25 3. The combination of a well-pipe, single-acting pumping means comprising two plungers adapted to be reciprocated in alinement with said well-pipe for forcing a supply of water into the well-pipe, two plunger rods connected with said plungers respectively for reciprocating them in opposite directions, other single-acting pumping means comprising two other plungers adapted to be reciprocated in alinement with said well-pipe below said first-named plungers for forcing a separate supply of water into said well-pipe, and connections between said plunger-rods and said last-named plungers 40 respectively, said connections comprising a pipe communicating with said lower plungers and adapted to conduct the water pumped by the said lower plungers past the upper plungers and to deliver it into said well pipe.

50 4. The combination of a well-pipe, single-acting pumping means adapted to be reciprocated in alinement with said well-pipe and adapted to take a supply of water at its lower end from the well and to deliver it to said well-pipe, and other single-acting pumping means adapted to be reciprocated in alinement with said well-pipe above said first-named pumping means and adapted to 55 take a separate supply of water at its lower end, from said well above said first-named pumping means and to deliver it to said well-pipe.

60 5. In a pump, the combination of a pump-rod, two plungers adapted to be reciprocated

by said pump rod, a second pump rod, two plungers adapted to be reciprocated by said second pump rod between said first-named two plungers, and means for reciprocating said pump rods whereby the upper two plungers coöperate for pumping and the lower two plungers coöperate for pumping.

65 6. In a pump, the combination of a well-pipe, a pump rod, two plungers adapted to be reciprocated by said pump rod, a second 70 pump rod, two plungers adapted to be reciprocated by said second pump rod between said first-named two plungers, stationary closure means interposed between the second-named two plungers serving to prevent communication between them, a pipe opening below said stationary closure means and communicating with said well-pipe above said several plungers, and means for reciprocating said pump rods whereby the upper two 75 plungers coöperate for pumping a supply of water into said well-pipe and the lower two plungers coöperate for pumping a separate supply of water into said well-pipe.

80 7. In a pump, the combination of a pump-rod, two plungers adapted to be reciprocated by said pump rod, a second pump rod, two 85 plungers adapted to be reciprocated by said second pump rod between said first-named two plungers, and means for reciprocating said pump rods whereby the upper two plungers coöperate for pumping and the lower two 90 plungers coöperate for pumping, each of said plungers comprising an upwardly-opening valve therethrough.

95 8. In a pump, the combination of a well-pipe, two cylinders one below the other in alinement with each other and with said well-pipe, each of said cylinders being adapted to receive water freely at its lower 100 end, means for closing one of said cylinders from the other cylinder, means connecting the well-pipe with the upper end of each of said cylinders, two plungers in each of said cylinders adapted to be reciprocated therein for forcing water upward into said well-pipe, means for reciprocating the intermediate two plungers in unison, and means for reciprocating the other two plungers in unison.

105 9. In a pump, the combination of a well-pipe, a cylindrical pump rod therein, a tubular pump rod extending through said cylindrical pump rod, a third pump rod extending through said tubular pump rod, a 110 plunger connected with said cylindrical pump rod and adapted to be reciprocated therewith, two plungers connected with said tubular pump rod and adapted to be reciprocated therewith below said first-named pump rod, and a fourth plunger connected with said third pump rod and adapted to be reciprocated therewith, said uppermost two plungers being adapted to coöperate for forcing a supply of water into said well-115

pipe and said lowermost two plungers being adapted to coöperate for forcing another supply of water into said well-pipe.

10. In a pump, the combination of a well-
5 pipe, a cylindrical pump rod therein, a tu-
bular pump rod extending through said cy-
lindrical pump rod, a third pump rod ex-
tending through said tubular pump rod, a
plunger connected with said cylindrical
10 pump rod and adapted to be reciprocated
therewith, two plungers connected with said
tubular pump rod and adapted to be recip-
rocated therewith below said first-named
15 pump rod, a fourth plunger connected with
said third pump rod and adapted to be recip-
rocated therewith, and means for reciprocating
said first-named pump rod and said
third pump rod in unison.

11. In a pump, the combination of a well-
20 pipe, a cylindrical pump rod therein, a tu-
bular pump rod extending through said cy-
lindrical pump rod, a third pump rod ex-
tending through said tubular pump rod, a
plunger connected with said cylindrical
25 pump rod and adapted to be reciprocated
therewith, two plungers connected with said
tubular pump rod and adapted to be recip-
rocated therewith below said first-named
pump rod, and a fourth plunger connected
30 with said third pump rod and adapted to be
reciprocated therewith, said uppermost two
plungers being adapted to coöperate for
forcing a supply of water into said well-
pipe and said lowermost two plungers being
35 adapted to coöperate for forcing another
supply of water through said tubular pump
rod into said well-pipe.

12. In a pump, the combination of a well-
40 pipe, a pump rod, two plungers adapted to
be reciprocated by said pump rod, a second
pump rod, two plungers adapted to be recip-
rocated by said second pump rod between
said first-named two plungers, and means for
45 reciprocating said pump rods whereby the
upper two plungers coöperate for raising a
supply of water into said well-pipe and the
lower two plungers coöperate for raising
another supply of water into said well-pipe,
said pump rods and said plungers being
50 adapted to be drawn upward from the well
through said well-pipe.

13. In a pump, the combination of a well-
55 pipe, a cylinder connected to the lower end
of said well-pipe and communicating there-
with, a second cylinder of smaller diameter
connected to the lower end of said first-
named cylinder but closed from communica-
tion therewith, an opening from the lower
60 end of said first-named cylinder into the
well, plungers operating in said cylinders
adapted to force water upward into said
well-pipe, and a pipe opening into the upper
end of said second cylinder and leading
65 into said well-pipe above said first-named
cylinder.

14. In a pump, the combination of a well-
70 pipe, a cylinder connected to the lower end
of said well-pipe and communicating there-
with, a second cylinder of smaller diameter
connected to the lower end of said first-
named cylinder but closed from communica-
75 tion therewith, an opening from the lower
end of said first-named cylinder into the
well, two plungers in each of said cylinders,
means for reciprocating the plungers in each
cylinder in opposite directions for forcing
75 water upward into said well-pipe, and a pipe
opening into said second cylinder above both
of the plungers therein and leading into said
well-pipe above said first-named cylinder. 80

15. In a pump, the combination of a well-
85 pipe, a cylinder connected to the lower end
of said well-pipe and communicating there-
with, a second cylinder of smaller diameter
below said first-named cylinder, a taper-
ing coupling connecting said two cylinders,
85 a closure member having a corresponding
taper seated in said coupling adapted to
close the upper end of said second cylinder
but having an opening leading into the lower
end of said first-named cylinder, plungers
90 operating in said cylinders adapted to force
water upward into said well-pipe, and a pipe
opening into the upper end of said
second cylinder and leading into said well-
95 pipe above said first-named cylinder.

16. In a pump, the combination of a well-
100 pipe, a cylinder connected to the lower end
of said well-pipe and communicating there-
with, a second cylinder of smaller diameter
below said first-named cylinder, a tapering
coupling connecting said two cylinders, a
105 closure member having a corresponding ta-
pered seat in said coupling adapted to close
the upper end of said second cylinder but
having an opening leading into the lower
end of said first-named cylinder, packing
110 interposed between said closure member and
said first-named cylinder, packing inter-
posed between said closure member and said
second cylinder, plungers operating in said
cylinders adapted to force water upward
115 into said well-pipe, and a pipe opening into
the upper end of said second cylinder and
leading into said well-pipe above said first-
named cylinder.

17. In a pump, the combination of a cyl-
120 inder, a tubular pump rod extending down-
ward thereinto, means for closing the lower
end of said cylinder about said tubular
pump rod, a plunger connected with said
tubular pump rod in said cylinder, a second
125 pump rod extending through said tubular
pump rod, and a plunger connected with
said second pump rod in said cylinder be-
low said first-named plunger, said tubular
pump rod opening into said cylinder above
said first-named plunger.

18. In a pump, the combination of a cyl-
130 inder, a tubular pump rod extending down-

ward thereinto, means for closing the lower end of said cylinder about said tubular pump rod, a plunger connected with said tubular pump rod in said cylinder, a second pump rod extending through said tubular pump rod, and a plunger connected with said second pump rod in said cylinder below said first-named plunger, said tubular pump rod opening into said cylinder above said first-named plunger and both of said plungers being provided with upwardly-opening valves whereby upon the reciprocation of said plungers, with the lower end of said cylinder in communication with a supply of water, the water is forced upward out of said cylinder through said tubular pump rod.

19. In a pump, the combination of a cylinder, a tubular pump rod extending downward thereinto, means for closing the lower end of said cylinder about said tubular pump rod, a plunger connected with said tubular pump rod in said cylinder, a second pump rod extending through said tubular pump rod, a plunger connected with said second pump rod in said cylinder below said first-named plunger, said tubular pump rod opening into said cylinder above said first-named plunger and both of said plungers being provided with upwardly-opening valves whereby upon the reciprocation of said plungers, with the lower end of said cylinder in communication with a supply of water, the water is forced upward out of said cylinder through said tubular pump rod, and an upwardly-opening valve adapted to close the lower end of said cylinder.

20. In a pump, the combination of a well-pipe, a cylindrical pump rod therein, a tubular pump rod extending through said cylindrical pump rod, packing between said cylindrical pump rod and said tubular pump rod to prevent the escape of water therebetween, a third pump rod extending through said tubular pump rod, a plunger connected with said cylindrical pump rod and adapted to be reciprocated therewith, two plungers connected with said tubular pump rod and adapted to be reciprocated therewith below said first-named pump rod, and a fourth plunger connected with said third pump rod and adapted to be reciprocated therewith, said uppermost two plungers being adapted to coöperate for forcing a supply of water into said well-pipe and said lowermost two plungers being adapted to coöperate for forcing another supply of water into said well-pipe.

21. In a pump, the combination of a cylinder, a second cylinder connected at its upper end with the lower end of said first-named cylinder, a tubular pump rod extending down through said first-named cylinder into said second cylinder and opening therewith, a valve-cage closing the up-

per end of said second cylinder about said tubular pump rod and providing an opening from said first-named cylinder independently of said second cylinder, a valve carried by said valve-cage adapted to close the opening therethrough, a plunger mounted on said tubular pump rod in said first-named cylinder, and a second plunger mounted on said tubular pump rod in said second cylinder below the opening from said pump rod into said cylinder, both of said plungers being provided with upwardly-opening valves.

22. In a pump, the combination of a cylinder, a second cylinder below said first-named cylinder, a coupling connecting said two cylinders, a tubular pump rod extending down through said first-named cylinder into said second cylinder and opening therewith, a valve-cage having a tapering seat in said coupling, a packing interposed between said valve-cage and said tubular pump rod, a second packing interposed between said valve-cage and said first-named cylinder, a third packing interposed between said valve-cage and said second cylinder, said valve-cage serving to close the upper end of said second cylinder about said tubular pump rod but being adapted to be lifted readily out of position, a valve carried by said valve-cage adapted to close an opening through said valve-cage leading from the lower end of said first-named cylinder, a plunger mounted on said tubular pump rod in said first-named cylinder, and a second plunger mounted on said tubular pump rod in said second cylinder, both of said plungers being provided with upwardly-opening valves.

23. In a pump, the combination of a tubular pump rod, a second pump rod extending through said tubular pump rod, two plungers spaced a short distance apart and connected with said second pump rod, two other plungers located between said first-named plungers and connected with said tubular pump rod, the upper two plungers being adapted to coöperate for pumping and the lower two plungers being adapted to coöperate for pumping.

24. In a pump, the combination of a well-pipe, a tubular pump rod therein, a second pump rod extending through said tubular pump rod, two plungers spaced a short distance apart and connected with said second pump rod, two other plungers located between said first-named two plungers and connected with said tubular pump rod, the upper two plungers being adapted to coöperate for raising a supply of water into said well-pipe, and the lower two plungers being adapted to coöperate for raising another supply of water through said tubular pump rod into said well-pipe.

25. In a pump, the combination of a tubu-

- lar pump rod, a second pump rod extending through said tubular pump rod, a short pump rod section outside of said tubular pump rod near the lower end of the tubular 5 pump rod, means for connecting said third pump rod with said second pump rod for causing them to move in unison, and plungers connected with said respective pump rods.
- 10 26. In a pump, the combination of a tubular pump rod, a second pump rod extending through said tubular pump rod, a short cylindrical pump rod section surrounding said tubular pump rod near the 15 lower end of the tubular pump rod, means for connecting said cylindrical pump rod with said second pump rod for causing them to move in unison, and plungers connected with said respective pump rods.
- 20 27. In a pump, the combination of a well-pipe, a tubular pump rod therein, a second pump rod extending through said tubular pump rod, a short pump rod section outside of said tubular pump rod near the lower end 25 of the tubular pump rod, means for connecting said third pump rod with said second pump rod for causing them to move in unison, and plungers connected with said respective pump rods, the water pumped by 30 the lowermost two plungers being delivered into the well-pipe through the said tubular pump rod through an opening above the up- permost plunger.
28. In a pump, the combination of a tubular pump rod comprising two sections spaced 35 a distance apart, links connecting said two sections rigidly together, a second pump rod extending through said tubular pump rod, a third pump rod extending alongside of said 40 links, means for connecting said second pump rod and said third pump rod to cause them to move in unison, and plungers connected with said respective pump rods.
29. In a pump, the combination of a tubular pump rod comprising two sections spaced 45 a distance apart, links connecting said two sections rigidly together, a second pump rod extending through said tubular pump rod, a cylindrical pump rod surrounding said links 50 and said second pump rod, a head mounted on said second pump rod having arms extending between said links for connection to said third pump rod for causing said third pump rod to move in unison with said sec- 55 ond pump rod, and plungers connected with the respective pump rods.
30. In a pump, the combination of a tubular pump rod comprising two sections spaced a distance apart, links connecting said two 60 sections rigidly together, a second pump rod extending through said tubular pump rod, a cylindrical pump rod surrounding said links and said second pump rod, packing between 65 said cylindrical pump rod and said tubular pump rod, a head mounted on said second pump rod having arms extending between said links for connection to said third pump rod for causing said third pump rod to move in unison with said second pump rod, and plungers connected with the respective pump rods.
31. The combination of a well-pipe, a tubular pump rod therein comprising a plurality of sections and coupling sleeves for connecting the adjacent ends of said sections together, said coupling sleeves being provided on their outer faces with guiding means for holding said tubular pump rod centered relative to said well-pipe, a second pump rod extending through said tubular pump rod, and a plurality of bearings one mounted in each of said coupling devices adapted to hold said second pump rod centered relative to said tubular pump rod. 75
32. The combination of a well-pipe, a tubular pump rod therein comprising a plurality of sections and coupling sleeves for connecting the adjacent ends of said sections together, each of said coupling sleeves having formed integrally with it a bearing 80 sleeve engaging said well-pipe and serving to hold said tubular pump rod centered relative to said well-pipe, a second pump rod extending through said tubular pump rod, and a plurality of bearings one mounted in each 85 of said coupling devices adapted to hold said second pump rod centered relative to said tubular pump rod. 90
33. The combination of a well-pipe, a tubular pump rod therein comprising a plurality of sections and coupling sleeves for connecting the adjacent ends of said sections together, each of said coupling sleeves having a plurality of webs extending radially from its outer face, bearing sleeves mounted on 95 said webs about said coupling sleeves adapted to hold said tubular pump rod centered relative to said well-pipe, a second pump rod extending through said tubular pump rod, and a plurality of bearings one mounted in each 100 of said coupling devices adapted to hold said second pump rod centered relative to said tubular pump rod. 105
34. In a pump, the combination of two pump rods, means for reciprocating said pump rods in opposite directions, plungers mounted on said pump rods, and cylinders in which said plungers are operative for raising water only upon their upward strokes, the plungers mounted on each pump rod being adapted upon each upward stroke of said pump rod to lift a quantity of water approximately equal to the capacity of one 110 of the cylinders. 115
35. In a pump, the combination of a tubular pump rod, a second pump rod extending through said first-named pump rod, means for reciprocating said pump rods in opposite directions, four plungers two of which are connected with each of said pump 120 rods. 125
- 130

rods, and two cylinders in which said plungers are operative for raising water only upon their upward strokes, one of the plungers connected with each pump rod being 5 operative in each of said cylinders, and the two plungers connected with each pump rod being adapted on each upward stroke of the said pump rod to lift a quantity of water approximately equal to the effective capacity 10 of one of the cylinders.

36. In a pump, the combination of two pump rods, means for reciprocating said pump rods in opposite directions; a plurality of plungers mounted on each of said 15 pump rods, and a plurality of cylinders in which each of said plungers is operated for raising water only upon their upward stroke, the plungers mounted on each pump

rod being adapted for each upward stroke of said pump rod, to lift its proportion of 20 water approximately the capacity of the cylinders in which said plunger operates.

37. In a pump, the combination of a plurality of pump rods, one rod operating inside of the other rod, means for reciprocating 25 said pump rods in opposite directions; a plurality of plungers connected to and operated by each plunger rod, and a plurality of cylinders in which said plungers are operated for raising water only upon their up 30ward stroke.

LARS W. BODINSON.
